UNITED STATES PATENT OFFICE.

JAMES C. KELLOGG, JR., OF ELIZABETH, NEW JERSEY, ASSIGNOR TO EPHRAIM WILLIAMS, OF NEW YORK, N. Y.

LIQUID-STORING DEVICE.

965,196.

Specification of Letters Patent. Patented July 26, 1910.

Application filed March 13, 1909. Serial No. 483,323.

To all whom it may concern:

Be it known that I, JAMES C. KELLOGG, Jr., a citizen of the United States, residing at Elizabeth, in the county of Union and State 5 of New Jersey, have invented certain new and useful Improvements in Liquid-Storing Devices, of which the following is a full, clear, and exact description, such as will enable others skilled in the art to which it applies 10 to make and use the same.

This invention relates to hydrocarbon tanks for automobiles, autoboats, and the like.

One of the objects is to provide a practical 15 storage device comprising an auxiliary receptacle adapted to contain a reserve supply of liquid, which may be utilized after the main supply has been exhausted.

Another object is to provide a device of 20 this character the parts of which are so constructed and arranged as to positively insure the filling of the auxiliary receptacle before the filling of the main receptacle, and to permit ready use of the contents of the 25 former when required.

Another object is to so arrange the auxiliary receptacle that its contents can only be discharged therefrom by a positive act, thereby eliminating any danger of its being 30 accidentally discharged or emptied.

Other objects will be in part obvious and in part pointed out hereinafter.

The invention accordingly consists in the 35 features of construction, combinations of elements and arrangement of parts which will be exemplified in the construction hereinafter set forth, and the scope of the application of which will be indicated in the following claims.

40 In the accompanying drawings, wherein is shown one of various possible embodiments of the invention, Figure 1 is a sectional view of this apparatus taken partially on the line $x-x$ of Fig. 2; Fig. 2 is a 45 sectional view taken on the line $y-y$ of Fig. 1; Fig. 3 is a view similar to Fig. 2 showing the auxiliary tank in its discharging position.

Similar reference characters refer to similar parts throughout.

Before entering into a description of the specific features of the invention, and as conducive to a clear understanding of the objects thereof, it may here be noted that

in the majority of the liquid fuel storage 55 tanks now in use in automobiles and like relations, unless careful attention is given to the same there is a possibility that the supply of liquid will give out during the trip, thereby causing great inconvenience, 60 as the nearest place at which a fresh supply of the liquid can be procured may be at some distance. The above and other inconveniences are entirely eliminated by the device hereinafter described. 65

Referring to the drawing, in which similar reference numerals refer to similar parts throughout the several views, 1 indicates the main receptacle or tank which is preferably cylindrical as shown and provided with inlet and outlet openings 2 and 3, the former of which is adapted to be closed by a suitable plug 4 and the latter of which communicates through conduit 5 with the carbureter 6 or other device to which the liquid 70 is to be led from the receptacle. In the preferred construction the receptacle is composed of two cup-shaped sections 7 and 8 placed with their open ends abutting within a collar 9 to which they may be secured in 75 any suitable manner, as, for example, by brazing, thus providing a receptacle which is seamless and free from rivet holes, thereby avoiding all danger of leakage. If desired, an air vent 10 may be provided in the 80 upper surface of the receptacle.

Oppositely disposed supporting members 11 are positioned within the receptacle 1 at the ends thereof, being secured therein in any suitable manner, and have perforations 90 formed therein within which pivots 12 of an auxiliary receptacle 13 are adapted to be journaled. The auxiliary receptacle or tank 13 is provided with an opening 14 in its wall through which the liquid is adapted 95 to pass and its normal position is such that the opening will be uppermost. While any suitable means may be employed to maintain the auxiliary tank in its normal position, the preferred construction, as clearly shown 100 in the figures, comprises a weight 15 secured to the lower portion of the auxiliary receptacle in any suitable manner, said weight being sufficient to cause said receptacle automatically to assume a position such that the opening 14 formed therein registers with the inlet opening 2 of the main receptacle 1. 105 The means for moving the auxiliary recep-

tacle into discharging position comprises a flexible member 16 such as a chain, one end of which is secured to the auxiliary receptacle 13 preferably above its central axis, 5 and the other end of said member is secured to a retaining device 17 which is pivotally mounted in the plug 4. The length of the flexible member 16 is such that when the plug is in position said member will be in a slack condition, as clearly indicated in Fig. 2, whereby the plug may be removed in order to charge the receptacle with fluid without causing any movement of the auxiliary receptacle. When it is desired to discharge the contents of the auxiliary receptacle, it is merely necessary to draw the plug upward, thereby causing the flexible member to rotate the auxiliary receptacle upon its pivots as indicated in Fig. 3, the weight 15 10 contacting with a stop 18 secured to the casting of the main receptacle to limit the movement of the auxiliary receptacle.

The operation of the device, which should be largely obvious from the above description, is as follows: When it is desired to charge the receptacles with liquid, the plug 4 is removed without causing movement of the auxiliary receptacle 13 and the liquid is then poured through the inlet opening 2 25 in the main receptacle 1, and, as the opening 14 of the auxiliary receptacle is in registry therewith, it will, of course, be understood that the initial portion of the liquid will flow into said auxiliary receptacle until 30 it is completely filled, after which it will flow into the main receptacle, and when both of the receptacles are filled the plug is replaced in its proper position. The device is now in condition for use and the engine 35 may be operated by drawing the liquid from the main receptacle, as desired, in the usual manner. If the main supply should become exhausted the engine will, of course, stop, thereby warning the operator that it will be 40 necessary to proceed to an available liquid fuel depot in order to obtain a fresh supply of the liquid. It is then necessary to remove the plug 4 and draw the same upward, thereby causing the auxiliary receptacle to 45 assume its discharging position, permitting the liquid to flow therefrom into the main receptacle, as indicated in Fig. 3. The auxiliary receptacle is made of such a size 50 that it will contain a quantity of liquid sufficient to operate the conveyance an appreciable distance. After the auxiliary receptacle has been emptied in the manner above described, the plug will be replaced in position, thus permitting said receptacle to assume its normal position through the medium of the weight 15.

It will be seen from the above description that the device is compact and simple in its construction and that it will be positive in 65 its operation. The auxiliary receptacle will

always remain full of liquid until the liquid is discharged therefrom by a positive act of the operator which is readily and conveniently accomplished.

There is no danger of said auxiliary receptacle being discharged even when the automobile is ascending or descending a hill, as in either case the auxiliary receptacle will be maintained with its opening uppermost due to the action of gravity. 70

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense. 75

Having described my invention, what I 80 claim as new and desire to secure by Letters Patent is:

1. In a device of the class described, in combination, a receptacle adapted to receive a liquid and provided with an inlet opening, 90 an auxiliary receptacle adapted to receive a liquid, said auxiliary receptacle being movably mounted within said first receptacle and provided with an inlet opening, said auxiliary receptacle being normally maintained 95 in position with its inlet opening uppermost, means for moving said auxiliary receptacle into discharging position, and means for limiting its movement.

2. In a device of the class described, in combination, a receptacle adapted to receive a liquid and provided with an inlet opening, a carbureter connected with said receptacle and supplied therefrom, an auxiliary receptacle adapted to receive a liquid, said auxiliary receptacle being movably mounted within said first receptacle and provided with an inlet opening, said auxiliary receptacle being normally maintained by gravity in position with its inlet opening uppermost, 100 and manually controlled means for moving said auxiliary receptacle into discharging position whereby a reserve supply for said carbureter is brought into use. 105

3. In a device of the class described, in combination, a receptacle adapted to receive a liquid and provided with an inlet opening, 110 an auxiliary receptacle adapted to receive a liquid, said auxiliary receptacle being movably mounted within said first receptacle and provided with an inlet opening, said auxiliary receptacle being normally maintained in position with its inlet opening uppermost, and manually controlled means for moving said auxiliary receptacle into 115 discharging position.

4. In a device of the class described, in combination, a receptacle adapted to receive a liquid and provided with an inlet opening, an auxiliary receptacle adapted to receive a 120

liquid, said auxiliary receptacle being movably mounted within said first receptacle and provided with a normally open inlet, a weight associated with said auxiliary receptacle and adapted to maintain it in position with its inlet uppermost, and means operable from without the receptacle for moving said auxiliary receptacle into discharging position.

9 5. In a device of the class described, in combination, a receptacle adapted to receive a liquid and provided with an inlet opening, an auxiliary receptacle adapted to receive a liquid, said auxiliary receptacle being movably mounted within said first receptacle and provided with an inlet opening, a weight associated with said auxiliary receptacle and adapted to maintain it in position with its inlet opening uppermost, means for moving 15 said auxiliary receptacle into discharging position, and means co-acting with said weight to limit the movement of said auxiliary receptacle. 10 6. In a device of the class described, in combination, a receptacle adapted to receive a liquid and provided with an inlet opening, an auxiliary receptacle for containing a reserve supply of the same liquid, said auxiliary receptacle being movably mounted 20 within said first receptacle and provided with an inlet opening, said auxiliary receptacle being normally so positioned and having a normally open inlet aperture so shaped that when the liquid is poured into 25 the inlet opening of said first receptacle said auxiliary receptacle will be completely filled before said first receptacle will receive any of the liquid, and means for moving said auxiliary receptacle into discharging position. 30 7. In a device of the class described, in combination, a receptacle adapted to receive a liquid and provided with an inlet opening, an auxiliary receptacle for containing a reserve 35 supply of the same liquid, said auxiliary receptacle being movably mounted within said first receptacle and provided with an inlet opening, said auxiliary receptacle being normally so positioned that its inlet opening 40 registers with the inlet opening of said first receptacle, and means for moving said auxiliary receptacle into discharging position the passage between said inlet openings being normally unobstructed. 45 8. In a device of the class described, in combination, a receptacle adapted to receive a liquid and provided with an inlet opening, an auxiliary receptacle adapted to receive a liquid, said auxiliary receptacle being movably mounted within said first receptacle and provided with an uncovered inlet opening, said auxiliary receptacle being normally maintained in position with its inlet opening uppermost, and manually controlled 50 means secured to said auxiliary receptacle 55 for moving the same into discharging position.

9. In a device of the class described, in combination, a receptacle adapted to receive a liquid and provided with an inlet opening, a carbureter connected with and supplied from said receptacle, an auxiliary receptacle adapted to receive a liquid, said auxiliary receptacle being movably mounted within said first receptacle and provided with an inlet opening, said auxiliary receptacle being normally maintained in position with its inlet opening uppermost, and means operable from without the main receptacle secured to said auxiliary receptacle for moving the same into discharging position. 70 10. In a device of the class described, in combination, a receptacle adapted to receive a liquid and provided with an inlet opening, an auxiliary receptacle adapted to receive a liquid, said auxiliary receptacle being movably mounted within said first receptacle and provided with a normally uncovered inlet opening, said auxiliary receptacle being normally maintained in position with its inlet opening uppermost, and manually operated means secured to said auxiliary receptacle for moving the same into discharging position, said means being normally inclosed 75 within said first receptacle. 80 11. In a device of the class described, in combination, a receptacle adapted to receive a liquid and provided with an inlet opening, a closure for said opening, an auxiliary receptacle adapted to receive a liquid, 85 said auxiliary receptacle being movably mounted within said first receptacle and provided with an inlet opening, said auxiliary receptacle being normally maintained in position with its inlet opening uppermost, 90 and means extending between said closure and said auxiliary receptacle for moving the latter into discharging position, said means permitting the removal of said closure without disturbing the position of said auxiliary 95 receptacle. 100 12. In a device of the class described, in combination, a receptacle adapted to receive a liquid and provided with an inlet opening, a closure therefor, an auxiliary receptacle 105 adapted to receive a liquid, said auxiliary receptacle being movably mounted within said first receptacle and provided with an inlet opening, said auxiliary receptacle being normally maintained in position with its inlet opening uppermost, 110 and a flexible member having one end pivotally secured to said closure and its other end secured to said auxiliary receptacle whereby said auxiliary receptacle may be moved into discharging position, said 115 flexible member being slack, whereby said closure may be removed without disturbing the position of said auxiliary receptacle. 120 13. In a device of the class described, in combination, a tank, a second tank movably 125 secured to said auxiliary receptacle. 130

14. In a device of the class described, in combination, a receptacle adapted to receive a liquid and provided with an inlet opening, a closure therefor, an auxiliary receptacle adapted to receive a liquid, said auxiliary receptacle being movably mounted within said first receptacle and provided with an inlet opening, said auxiliary receptacle being normally maintained in position with its inlet opening uppermost, and a flexible member having one end pivotally secured to said closure and its other end secured to said auxiliary receptacle whereby said auxiliary receptacle may be moved into discharging position, said flexible member being slack, whereby said closure may be removed without disturbing the position of said auxiliary receptacle. 140

mounted therein to assume two positions, in the first of which it is adapted to retain its contents and in the second of which it tends to pour the same into the first tank, a carbureter connected with and supplied from said first tank, means adapted to move said second tank from said first to said second position, and automatically acting means adapted to return the same to said first position.

14. In a device of the class described, in combination, a tank, a second tank movably mounted therein to assume two positions, in the first of which it is adapted to retain its contents and in the second of which it tends to pour the same into the first tank, said tanks being provided with openings which substantially register with said inner tank in said first position, whereby said second tank is normally adapted to receive a liquid entering said first tank, means adapted to move said inner tank from said first to said second position.

15. In a device of the class described, in combination, a tank, a second tank movably mounted therein to assume two positions, in the first of which it is adapted to retain its contents and in the second of which it tends to pour the same into the first tank, said tanks being provided with openings which substantially register with said inner tank in said first position, whereby said second tank is normally adapted to receive a liquid entering said first tank, means adapted to move said inner tank from said first to said second position, and automatically acting means adapted to return the same to its first position.

position said second tank being of a capacity less than the space between said tanks.

25

15. In a device of the class described, in combination, a tank, a second tank movably mounted therein to assume two positions, in the first of which it is adapted to retain its contents and in the second of which it tends to pour the same into the first tank, said tanks being provided with openings which substantially register with said inner tank in said first position, whereby said second tank is normally adapted to receive a liquid entering said first tank, means adapted to move said inner tank from said first to said second position, and automatically acting means adapted to return the same to its first position.
